UNITED STATES PATENT OFFICE.

SIMON LAZARUS, OF LOUISVILLE, KENTUCKY.

NON-REFILLABLE BOTTLE.

1,214,329.

Specification of Letters Patent. Patented Jan. 30, 1917.

Application filed September 27, 1915. Serial No. 52,768.

To all whom it may concern:

Be it known that I, SIMON LAZARUS, a citizen of the United States, residing at Louisville, in the county of Jefferson and State of Kentucky, have invented certain new and useful Improvements in Non-Refillable Bottles, of which the following is a specification.

This invention relates to new and useful improvements in a non-refillable bottle.

The object of the invention is to provide a bottle which when once emptied cannot be practicably refilled.

With the above and other objects in view, the invention has particular relation to certain novel features of construction, operation and arrangement of parts an example of which is given in this specification and illustrated in the accompanying drawing 20 wherein:—

Figure 1 is a sectional side elevation of the device, Fig. 2 is a fragmentary plan view, Fig. 3 is an inverted vertical sectional view, Fig. 4 is a plan view of the valve mechanism employed, Fig. 5 is a side elevation thereof, partially in section and Fig. 6 is a bottom plan view thereof.

Referring now more particularly to the drawings wherein like numerals of reference 30 designate similar parts in each of the figures the numeral 1 refers to a bottle of conventional form having the reduced neck 2. Fitted within this neck is a thimble 3 which is secured in position by means of peripheral 35 teeth 4 which project into corresponding recesses 5 in said neck. The lower end of this thimble is reduced and surrounded by a close fitting bushing 6 formed of cork or other similar material which is interposed 40 between the thimble and the neck 2 preventing the escape of fluid around said thimble. The extreme lower end of the thimble is contracted at 7 forming a tapering seat in which fits a correspondingly shaped valve 8, 45 which when seated closes the lower end of the thimble. A tapped hole extends through this valve into the upper end of which is screwed the lower end of the outwardly

threaded rod 9, upon which is threaded the open disk 10. When the valve 8 is seated 50 this disk contacts against the tapering sides of the seat 7, and the disk may be adjusted up or down on the rod 9 as may be necessary to permit the complete seating of the valve. The upper end of the rod 11 is threaded into 55 the lower end of the tapped hole in the valve 8, and the lower end of this rod has the cross arm 12. The bottle is first filled and the thimble 3, with the valve mechanism described, is inserted and secured in the neck 60 thereof and the thimble is closed by means of the ordinary cork 13. When it is desired to empty the bottle cork 13 is removed and the bottle inverted as shown in Fig. 3. The weight of the valve assisted by the pressure 65 of the fluid against the disk 10 will unseat the valve and permit the fluid to pass out through the thimble 3. The cross arm 12 engaging against the end of the thimble will operate to hold the valve in the position 70 within the thimble as shown in Fig. 3. When the bottle is again turned upright the valve will drop into its original position and seat in and close the contracted end of the thimble and prevent refilling of the bottle. 75

What I claim is:—

The combination with a bottle having a reduced neck, of a thimble seated in said neck whose lower end is contracted, forming a seat, a valve shaped to seat within the 80 contracted end of said thimble, a rod screwed into said valve and upstanding therefrom, an open disk threaded upon the free end of said rod and holding the valve centered relative to the seat, a rod threaded 85 into and depending from said seat and a cross arm carried by the lower end of said last mentioned rod.

In testimony whereof I have signed my name to this specification in the presence of 90 two subscribing witnesses.

SIMON LAZARUS.
